(57) **CLAIM**

The ornamental design for an indoor wall unit, as shown and described.

DESCRIPTION

FIG. 1 is a front perspective view of the indoor wall unit showing our new design;

FIG. 2 is a front view thereof;

FIG. 3 is a rear view thereof;

FIG. 4 is a left side view thereof where the right side view is a mirror image;

FIG. 5 is a top view thereof;

FIG. 6 is a bottom view thereof; and,

FIG. 7 is another front perspective view in a state of use with environment.

The broken lines, showing widgets displayed on the front right surface in FIG. 7, illustrate environment that forms no part of the claimed design.
